BRYANT DEDMAN, OF GLEN ELLYN, ILLINOIS

CASING HOOK FOR OIL WELLS

Application filed May 28, 1928. Serial No. 281,148.

This invention relates to hooks of the type employed for supporting and handling the casings and drill pipes and drill stems used in construction and operation of oil and gas wells.

Hooks of this type are commonly used, in putting in or pulling well casings, to support a section of the casing while it is being screwed or unscrewed from the other sections. The separation of the sections is effected by rotating the casing or drill rod, at a point below the joint to be broken, by means of a rotary table, while the section above the joint is held stationary by suitable tongs or by holding stationary the casing or drill rod, at a point below the joint to be broken, by means of a locked and suitably bushed rotary table while the section above the joint is rotated by means of tongs.

In either procedure some means is provided to take up the weight of the upper section during the breaking of the joint; the weight of the section rests on the screw threads of the joint and tends to grind off and damage the threads. To obviate this damage to the screw threads and to save time, it is common to support the section being removed by a casing hook provided with a compression spring of such strength as to support the said section during the breaking of the taper threaded joint and later after parting of the threads to automatically lift said section high enough to free it from all interference with its former mating member. Good examples of this type of casing hook is disclosed in the patent to Wigle, No. 14,253, reissued January 23rd, 1917; Keim, No. 1,572,390, February 9th, 1926; and Montgomery No. 1,536,617, May 5th, 1925.

The main object of the present invention is to so contrive the springs that the hook will have only a small excess spring lifting capacity at the bottom of its travel over that required at the top of its travel and thereby provide ample section lifting capacity at the top of hook travel without excessive lifting pressure on the partially disengaged threads at or near the bottom of the hook travel, that is, the point at which joints are broken, and

thereby prevent unnecessary wear and tear on the joints.

A further object of the invention is to reduce the shock within the hook mechanism itself.

The principal demand for casing hooks, at the present day, is for the handling of "thrables" or "fourbles" in rotary drilling; and casing hooks of the old type are not capable of handling these loads efficiently and without unnecessary shock within the hook mechanism itself. 55

In one typical size and type of casing hooks, similar to Wigle in common use, the spring when merely supporting a "fourble" 65 load (that is at the top of the travel of the spring) is compressed about three inches (3''); and, at the bottom of its travel (when the spring effect is used to raise the section during the unscrewing of the joint) has a 70 further compression of about seven inches (7''), making a total compression of ten inches.

Now, since the ordinary fourble load for this size hook is about 2500 lbs., and this 75 causes a three inch compression of the spring, it is obvious that a ten inch compression of the spring means that a load of over 8000 lbs. is imposed thereon at the start of the unscrewing operation or over three times in excess 80 of that required imposed upon partially disengaged threads. The present day made up fourble joints are decidedly taper threaded and separate at about one inch of vertical travel between the shoulders; that is, when the 85 spring would be compressed at about 7,500 lbs. Since the load of the fourble alone at this instant of joint separation is only 2500 lbs., there is a force of 5000 lbs. acting to throw the load upwardly with an evident 90 tendency to rip out threads immediately before and at the point of release. The shock on the spring and other mechanism of the hook in this case is sometimes great enough to jar loose parts of the assembly; and in all 95 events, imposes a great strain on such parts with consequent rapid deterioration thereof.

Field operators complain about what they term unnecessary strength in the springs employed, and demand hooks with lighter 100

springs, but they do not realize that lighter springs in these old type hooks will not carry the fourble load to the top of the loaded hook travel, which, to meet present day methods, should be at least 7" on the larger size hooks, the distance required to lift the pin clear of the box when unscrewed.

The present invention is designed to practically eliminate excess pressure on partially unthreaded joints of the sections and excess shock to both joints and hook mechanism due to recoil when the section is released. It is designed to carry the fourble load, for example, 2500 lbs. at the top of its travel and to exert a lifting force only slightly in excess of the fourble load, in this example, 3000 lbs., at the bottom of its travel. The result of this arrangement is that the toggle and spring construction exert sufficient force, at the instant of separation of a section from the casing, to lift the fourble load substantially without shock to the desired upper limit of travel.

The main objects of the present invention are, therefore, to provide an auto-compensating spring swivel casing hook capable of efficiently handling the "thribles" or "fourbles" in rotary drilling, and to eliminate practically all shock to the parts of swivelled spring casing hooks due to recoil of the springs.

Other objects of the invention will appear as the detailed description proceeds.

In the drawings:

Figure 21 is a section taken on the line 21—21 of Figure 20.

As shown in Figures 1, 4, and 5, 1 designates a hook adapted to receive the bights of a casing elevator 2 (see Figure 4). This hook 1 is formed integrally with a cylindrical rod 3 slidably mounted in a rectangular block 4 having trunnions 5 and 6 extending from opposite sides thereof to receive the apertures 7 and 8 in arms 9 and 10, respectively, of the yoke 11.

The block 4 is provided with a cylindrical bore 12 to form a guideway in which the rod 3 reciprocates. The rod 3 is provided with shoulders 13 and 14 adapted to contact with the lower and upper ends, respectively, of block 4, at the upper and lower limits of travel, respectively, of the hook 1. In this particular case, the block 4 is seven inches shorter than the distance between the shoulders 13 and 14 in order to restrict the movements of the hook to the seven inch limit above referred to.

In order to facilitate assembling of the block 4 and the rod 3, the block may be formed of two halves as shown in Fig. 12; and these halves, when assembled around rod 3, are riveted together and to the plates 17 and 18 by means of the rivets 19.

The upper end of rod 3 is screwthreaded into a cap 20 which is then locked non-rotatably by a pin 21 to said end. The shoulder

14 on rod 3 is formed by the lower end of a bushing 22 which is slidably mounted on rod 3; and race members 23 and 24 and rollers 25 of a roller bearing are interposed between the bottom of cap 20 and the top of bushing 22.

The bushing 2 has diametrically opposite ears 26 and 27 formed thereon to receive the bifurcated ends 28 and 29 of cylinders 31 and 32, respectively; and pins 33 and 34 serve to secure said ends pivotally to said ears 26 and 27, respectively.

Cylindrical rods 35 and 36 are mounted slidably in cylinders 31 and 32, respectively, and have their lower ends pivotally connected by pivots 37 and 38 to the side walls 39 and 40 of casing members 41 and 42.

The casing members 41 and 42 are spaced apart by and are fixed to the side plates 17 and 18 by the bolts 43 and nuts 44.

The pivots 37 and 38 each comprises a cylindrical rod having a cap 45 formed on one end to seat against one of the sides of members 41 and 42, and this rod has a transverse slot 46 cut in its periphery just where it passes through the side 39. (See Figure 7). A plate 47 is pivoted at one end to swing freely on the wall 39 so that its end may seat in slot 46 and lock the pivot securely to the casing. To hold the plate 47 in locking position, a machine screw 48 engaging a threaded hole in wall 39 may be used.

A pin or rod 49 having one end thereof secured by a chain 50 to the wall of casing member 42 to prevent loss thereof is shaped to slide through a bore 51 in the polygonal top of cap 20, to prevent turning of the hook and casing when it is desired to hold the same. This rod 49 has a coil spring 52 secured to a pin 52' and abutting the cap 20; and a locking pin 53 passes diametrically through slot 53' in rod 49 near its other end to be held in locking engagement with one end of cap 20 by the compression of spring 52 after the pin 53 is beyond the slot 53' and turned one quarter of a revolution that is, 90 degrees toward the bottom.

The cylinders 31 and 32 and piston rods 35 and 36 are surrounded by compression springs 54 and 55 which abut at their opposite ends against shoulders 56 and 57 and 58 and 59 to form yielding supports for the sleeve 22.

The dotted line position of the parts (Figure 1) show that while the bushing 22 travels seven inches before it contacts with the upper end of block 4, the coil springs 54 and 55 are compressed only about one-half of this distance and about one-fourth of their length. On the scale shown in the drawing, the springs exert at their bottom position an upward force of about 3000 lbs; and at the top of their travel, an upward force of about 2500 lbs. which is almost correct when the hook is to be used for handling 6" fourbles.

Since the upward force just referred to decreases with the extension of the spring during the unscrewing of the section, it follows that the force remaining at the instant of separation of the section from the casing 70 (after about 1" of travel) the force is just about sufficient to raise the free section to the upper limit of its travel with very little shock to the parts of the casing hook or to threaded joint being separated. 75

The form of the invention shown in Figures 8 to 14, inclusive, is substantially the same as that already described, so far as the principle involved in its operation is concerned. This form does not include any 80 roller bearings to permit the hook supporting rod to rotate; and it is therefore assumed that the rotary movement can be taken care of by a common type double swivel roller bearing hook and suspending (bail shown) 85 the section above the joint being broken.

As shown in Figures 8 and 10, the bail 60 of a common double swivel hook, as at present used, to permit turning of the hook where no provision is made in the casing for this 90 purpose, is hung from a bail having bifurcated arms 61 and 62 provided with alined bearing apertures 63 and 64, respectively, to receive a pivot pin 65. The pin 65 is provided with a head 66 at one end thereof, and 95 has a retaining washer 67 secured to its other end by a headed screw 68, the pin being secured in said apertures 63 and 64 by said head and washer. The bail 60 receives the usual gudgeon 60' for supporting the common double swivel hook (not shown).

The pin 65 is rotatably mounted in a horizontal bore 69 formed in bearing cap 70 which is screwthreaded and pinned on to the lower end of a cylindrical rod 71 slidably 105 vertically in a rectangular cylinder block 72.

The block 72 is formed in two parts 73 and 74, provided with suitable cooperating recesses and projections to prevent lengthwise separation of said parts when assembled. 110 These parts 73 and 74 are provided with registering bores 75 to receive bolts 76 for securing said parts together between casing plates 77 and 78. The parts 73 and 74 are also provided with semi-cylindrical recesses 115 79 and 80, adapted, when the parts are assembled, to form a cylinder in which rod 71 is mounted to slide.

The upper end of rod 71 is provided with a shoulder 81 adapted to contact with the upper end of block 72 to limit the downward movement of the hook 60; and the rod 71 is provided with a key slot 82 adapted to receive a key plate 83 seated in a recess 84, formed in the part 74, and provided with apertures 85 adapted to register with the bores 75. The plate 83 is securely held in position by the bolts 76 when the parts 73 and 74 are assembled. 125

The plates 77 and 78, between which the 130

cylinder block 72 is bolted, are bolted in turn to casing members 86 and 87 by bolts 88, and extend upwardly above said members to form bearing plates 89 and 90, for a pivot pin 91.

5 Washers 92 and 93 space the plates 89 and 90 from side plates 94 and 95, of a traveling block 96, apertured to provide bearings in which the projecting ends of the pivot 91 are seated.

10 The upper end of rod 21 is flattened on opposite sides to provide oppositely disposed bearing lugs 97 and 98 apertured to receive pivot pins 99 and 100, respectively. Cylinders 101 and 102 are swung on the pins 99 and 100, respectively; and pistons 103 and 104 slide in said cylinders 101 and 102 are pivoted to the casing members 86 and 87 on pivots 105 and 106, respectively, the pivots being detachably secured to the casing members by locking plates 107 and 108 in the same manner as the corresponding pivots of the construction shown in Figure 4.

The cylinders 101 and 102 and the pistons 103 and 104 are provided with shoulders 109, 110, 111 and 112 to form abutments for the ends of compression springs 113 and 114.

15 The modification just described operates similarly to that shown in Figures 1 to 7 except that the hook supporting rod is keyed against rotation in the block 72.

20 The modification shown in Figures 15 to 20 shows a very compact arrangement of parts in which the toggle linkages, connecting the springs supports to the hook, are floated on bell cranks. In this form of the invention the casing comprises a pair of substantially circular plates 115 and 116 having aligned pivots 117 and 118 secured thereto, to pivot the arms 119 and 120 of a yoke for supporting the casing hook.

25 The arcuate ends 121 and 122 are hinged at their upper ends on pins 123 and 124, respectively; and have their free ends 125 and 126 flattened to be bolted to the lower end of the cylinder block 127 which is bolted or otherwise fixed between the sides 115 and 116 by bolts 128.

30 The hook rod 29 is mounted to slide vertically in block 127, and is provided with a shoulder 130 to limit the upward vertical movement of the rod in the block. The upper end of the rod 129 is screw threaded and pinned into a cap 131, and roller bearing members 132, 133 and 134 are interposed between the cap 131 and a sleeve 135 to permit the rod to rotate freely in block 127 and relatively to sleeve 135; the lower end 130' of which forms a stop to limit the downward movement of the rod 129.

35 The spring supports for the hook in this form of the invention are similar to those shown in the forms already described, but are pivoted to the casing so as to normally stand substantially vertical. These supports comprise lower piston members 136 and 137

pivoted at their lower ends on pivot pins 138 and 139, respectively, secured by cotter pins 140 and 141 between the side plates 115 and 116.

40 The lower ends of members 136 and 137 are expanded laterally to form bushings 142, extending between the side plates 115 and 116 to center the supports between said plates; and the cylindrical piston parts thereof are capped by cylinders 142 and 143 sliding thereon. The upper ends 144 and 145 of these cylinders are flattened to form bearings for pivot pins 146 and 147 which are locked in said ends by the set screws 148 and 149.

45 To connect the pivot pins 146 and 147 to the hook rod 129, bell cranks 150 and 151 are pivoted to swing on pins 152 and 153 fixed to the side plates 115 and 116. The bell crank 150 comprises a bushing 154 extending between the walls 115 and 116 and pivoted on pivot 152. Two arms, 155 and 156 extend radially from said bushing and have their free ends pivoted to the lower ends of links 157 and 158 which are pivoted to opposite ends of a bearing ear 159 formed on the sleeve 135.

50 The upper arms 160 or bell crank 150 are pivotally connected to pivot 146, while the upper arms 161 of bell crank 151 are pivotally connected to the pivot 147. The links 162 and 163 are pivotally connected at one end to a bearing ear 164 also formed on the sleeve 135 opposite to ear 159 and at their lower ends are pivoted to arms 165 and 166. 100

55 The links and bell cranks are symmetrically arranged relative to the axis of the rod 129, and serve to convert a small compression of the springs 167 and 168 into a comparatively large downward movement 105 of the rod 129, and vice versa.

60 In all the modifications disclosed herein, the side plates or hinged end plates may be readily moved to give access to the parts enclosed in the casing whenever it becomes necessary to replace or repair parts thereof. In all of these devices the increasing mechanical advantage of the toggle construction offsets the decrease in spring pressure resulting from decrease in compression from normal spring compression in cases where the spring carries the whole load directly. 115

65 By proper design the mechanism could be designed to provide the same load carrying capacities at the top and bottom of the spring travel. However, the constructions disclosed herein provide an excess load carrying capacity at the bottom of the spring travel in order to provide sufficient lifting force at the bottom to accelerate and carry the load the usual seven inches to the top of the spring travel. 120

70 The seven inch travel of the load is the normal travel required by present day construction. It must be understood, however, 125

that this invention is not to be limited in any way to constructions designed to effect this seven inch lift, as the parts may be relatively proportioned and designed to take care of any desired lift. The seven inch lift is merely described herein in order to give a specific example of the construction and uses of the invention.

10. The compression of the springs in these devices may be regulated by inserting washers, similar to washer 170 (Fig. 20^a) between the ends of the springs and the abutment shoulders on the cylinders and pistons around which the springs are coiled.

15. The compression of the springs to accommodate different loads may be regulated by mounting the pivot pins of the springs in bearings eccentrically mounted on the casing. For example in Figs. 8^a, 8^b, and 8^c, 20. the pivot pin 106^a is rotatably mounted in the casing and extends beyond the opposite sides of the casing.

One side of the casing has a square opening 171 adapted to receive a squared portion 172 of the pin 106^a, and the latter has a spline 173 engaging a corresponding slot in the eccentric bearing arbor or cylinder 174. Beyond the squared portion is an enlarged head 175 preferably flattened on two sides and the opposite end of the pin is threaded to receive a nut 176. By unscrewing the nut 176, the pin may be displaced axially to disengage the squared portion 172 from the opening 171 where it normally holds the pin 106^a from turning, so that by applying a wrench to the head 175, the pin 106^a may be turned to correspondingly rotate or turn the eccentric collar or cylinder 174 whereby to adjust the compression or tension of the spring without disconnecting the parts. Then, by again engaging the squared portion 172 with the opening 171 and tightening on the nut 176, the parts are held in adjusted position and the shaft or pin 45. 106^a held from turning. By having the bearing at the end of the piston 104 enlarged to rotatably receive the cylinder and the latter keyed to the pin, it is obvious that the adjustment is controlled by the rotation of the 50. pin or shaft, 106^a. By this means, rotation of the pin causes rotation of the cylinder to raise or lower the piston 104 against the pressure of the spring 114.

The use of shims or washers to regulate 55. the initial spring pressure would necessarily involve disassembling of the several parts for each or the two different adjustments 5, whereas the eccentric mounting could be operated from outside the casing to effect the 60. adjustment without disconnecting any of the parts of the hook.

What I claim is:

1. A block, a hook rod slidably and rotatably mounted on said block, compression springs 65. pivoted at one end to said block on opposite

sides of said rod, and means connecting the other ends of said springs pivotally to said rod.

2. A block, a hook rod slidably journaled in said block, and toggle mechanism pivoted to said block and pivotally connected to said rod to support said rod yieldingly on said block.

3. A block, a hook rod reciprocable in said block, means on said block and said rod to limit the reciprocation of said rod, and means pivoted to said block on opposite sides of said rod to support the rod yieldingly in one of its limits of reciprocation.

4. A block, a guide fixed thereto, a hook rod reciprocable in said guide and having stops adapted to engage the opposite ends of said guide to limit the reciprocations of said rod, and yielding means between said block and rod to hold the rod with one of its stops normally in contact with one end of said guide.

5. A block, a guide fixed thereto, a hook rod slidable in said guide, stops on said rod engageable with the ends of said guide, spring members having one end of each pivoted to said block on opposite sides of said rod and connected to said rod to form a toggle linkage supporting said rod with one of its stops in contact with one end of said guide.

6. A block, a guide integral with said block, a hook rod slidable in said guide, means on opposite sides of said guide carried by said rod through a predetermined distance in either direction, compressible yielding means pivoted to said block and rod to resist sliding thereof in one direction and arranged so that compression of said means through a predetermined distance results in movement of said rod through a greater distance.

7. A block, a guide fixed to said block, a hook rod slidable in said guide and having a shoulder engageable with one end of said guide, a cap fixed to the other end of said rod, a sleeve rotatable on said rod between said cap and the other end of said guide, an anti-friction bearing between said sleeve and cap, and yielding means pivoted to said block and sleeve to hold said rod normally with said shoulder against said one end of the guide.

8. A block, a cylindrical guide fixed to said block, a hook rod slidably and rotatably mounted in said guide, a shoulder on said rod engageable with one end of said guide, a stop fixed to said rod yieldable toggle mechanism pivoted to said block, and slidably and rotatably connected to said rod to engage said stop and maintain said rod normally with its shoulder in contact with the end of said guide, said rod being slidable through said block a predetermined distance against the yielding resistance of said mechanism.

9. A block, a rod slidably and rotatably mounted on said block, means for limiting the sliding movements of said rod in each direction on said block, and yielding toggle.

mechanism pivoted to said block and rotatably and slidably connected to said rod to maintain said rod normally in a predetermined position on said block.

5 10. A block, an anti-friction bearing, a hook supported by said bearing, resilient toggle mechanism symmetrically arranged relative to said hook and supporting said bearing, and means on said block to carry the 10 load when the said hook has been moved a predetermined distance from its normal toggle supported position.

11. A block, an anti-friction bearing, a hook passing through and supported by said 15 bearing, resilient toggle mechanism pivoted to said block and including a sleeve slidable on said hook and in supporting contact with said bearing, and a stop member on said block positioned to support said sleeve and carry 20 the load on said hook when the said mechanism has been moved to a predetermined position.

12. A block, an anti-friction bearing, a hook passing through and supported by said 25 bearing to rotate freely thereon, a sleeve rotatable on said hook, resilient means pivotally connected to opposite sides of said sleeve and to said block, and a stop fixed to said block to support said sleeve and bearing when 30 the resilient means has been compressed a predetermined distance.

13. A block, an anti-friction bearing, a hook passing through and supported by said 35 bearing to rotate freely thereon, a sleeve rotatable on said hook and in supporting contact with said bearing, resilient means pivoted to said block and connected to said sleeve to support said bearing yieldingly, and a stop on said block to engage said sleeve and 40 transfer the load from said resilient means to said block.

14. A block, an anti-friction bearing, a hook passing through and supported by said bearing, a sleeve rotatable, on said hook, yielding means pivoted to said block and sleeve to support said bearing, and means to relieve the load on said yielding means when the sleeve has moved through a predetermined distance.

50 15. A block, a hook, a sleeve in which said hook is rotatably supported, spring members pivoted to said block on opposite sides of said hook, bell cranks pivoted to said block on opposite sides of said hook and having one 55 arm of each pivoted to the free end of the adjacent spring member, and links pivotally connecting the other arms of said bell cranks to said sleeve.

16. In a casing hook for oil wells and the 60 like, a block, a guide fixed to said block, a rod slidable in said guide and having a shoulder engageable with one end of said guide, a shoulder at the other end of said rod, a sleeve rotatable on said rod between said 65 shoulder and the other end of said guide, an

anti-friction means between the sleeve and second named shoulder, and yielding means pivoted to the block and sleeve to hold said rods normally with said shoulder against one end of the guide.

70 In testimony whereof I affix my signature.
BRYANT DEDMAN.
